OVERHEAD DOOR CLOSER

Norman Harold Edgley, Birmingham, England, assignor
to William Newman & Sons Limited, Birmingham,
England, a British company

Filed Aug. 5, 1963, Ser. No. 76,106

Term of patent 14 years

(Cl. D10—7)

FIG. 2.

FIG. 3.

FIG. 4.

I claim:

The ornamental design for an overhead door closer, as shown.
